[57] CLAIM

The ornamental design for a combined shoe tree and
shoe horn, as shown and described.

DESCRIPTION

FIG. 1 is a top plan view of a combined shoe tree and
horn showing my new design;

FIG. 2 is a front elevational view thereof;

FIG. 3 is a right side elevational view thereof, the left
side being a mirror image thereto;

FIG. 4 is a rear elevational view thereof; and

FIG. 5 is a bottom plan view thereof.

The characteristic feature of my design resides in the
configuration of the toe plate.
